UNITED STATES PATENT OFFICE

WILLIAM F. KIESEL, JR., OF ALTOONA, PENNSYLVANIA

THROTTLE VALVE

Application filed January 18, 1928. Serial No. 247,714.

This invention relates to throttle valves and more particularly to throttle valves adapted for use on steam locomotives and similar devices.

5 The various features of novelty and objects of the present invention may be enumerated as follows:

A. The provision of a throttle valve housing which forms the sole closure for one end 10 of a steam drum which may be on the exterior of the boiler barrel.

B. The arrangement of the throttle valve on the exterior of the boiler barrel, the superheater on the interior of the smoke-box and 15 the provision of a conduit or dry pipe passing through the wall of the smoke-box and connecting the two parts.

C. The arrangement of the throttle valve entirely outside of the boiler.

20 D. The provision of a casing within the valve housing having connection with the outlet conduits and of means to provide balancing steam to the bottom of said casing from near the top of said housing.

25 E. The manner of operating the valve without resorting to packing or sliding operating rods.

In more or less conventional locomotives it has been customary to locate the throttle 30 valve within the boiler barrel, in a suitable steam dome, and to lead the dry pipe from the valve to the cylinders through the front flue sheet and thus into the smoke-box. The present invention obviates a number of the 35 well-known difficulties experienced with that form of construction. It is particularly suitable for use with that type of locomotive boiler disclosed in my co-pending application Serial No. 202,521, filed June 30, 1927.

40 The invention may be understood best after a consideration of the accompanying drawings and following specification, wherein is disclosed a single exemplary embodiment thereof, with the understanding, however, that such changes may be made therein as fall within the scope of the appended claims, without departing from the spirit of the invention.

In said drawings:

50 Figure 1 is a side elevation of a locomotive

having a throttle valve constructed according to the present invention applied thereto, certain parts being omitted for the sake of simplicity;

Figure 2 is a longitudinal vertical section 55 through the throttle valve housing;

Figure 3 is a transverse section through the valve housing taken on line 3—3 of Fig. 2; and

Figure 4 is a partial horizontal section 60 taken on line 4—4 of Fig. 2.

Referring particularly to Fig. 1, the locomotive will be seen to include the boiler barrel 10, extending from the fire-box 11 to the smoke-box 12, which is just forward of the front flue sheet 13. Lying above and substantially parallel to the boiler barrel is the outside steam drum 14 in the form of a cylinder of small diameter having communication with the interior of the boiler barrel by means of the fitting 15. The rear end of the steam drum extends over the fire-box and is closed by a suitable fitting 16. The front end extends up to near the front flue sheet and is cut off substantially square as at 17. This steam drum takes the place of the customary steam dome and insures dry steam for the power cylinders.

Within the smoke-box are a pair of superheaters 18, one for each cylinder 19 of the 80 locomotive and connected to the steam chest thereof as at 20. The superheaters, of which but one is visible, are connected together by the cross-balance header 21.

The inlet header 22 of each superheater extends upwardly and through a suitable aperture in the wall of the smoke-box and is provided with a coupling flange 23 on the end thereof. The means for sealing the opening through the smoke-box wall, while yet allowing relative movement of the header 22 due to expansion and contraction resulting from temperature changes, is disclosed in my co-pending application Serial No. 205,019, filed July 11, 1927.

Steam from the drum 14 is introduced into the headers 22 through the conduit sections 24 which are connected to the drum through the agency of the throttle valve housing 25.

Referring now to Figs. 2, 3 and 4, it will 100

be seen that the housing 25 is preferably a one-piece casting having the neck or sleeve 26 adapted to fit tightly within the end of the drum 14 and be secured therein by suitable fastening means such as the rivets shown. It thus forms the sole closing means for the forward end of the steam drum. The open upper end of the housing is closed by the cover 27 suitably bolted in position.

10 Within the housing and integral with the forward wall thereof is the valve casing 28, the interior of which is connected to the conduit sections 24 by the laterally disposed integral conduits 30 which pass through the 15 walls of the housing as shown in Fig. 3. The flow of steam into the casing, and hence to the superheaters, is controlled by the valve 31 seating in the open upper end of the casing 28. The casing and the valve are constructed according to the disclosure in my 20 Patent No. 1,275,041, Throttle valve, issued August 6, 1918, and need not be further described here except to state that the valve is of the balanced type to reduce the amount 25 of effort necessary to move the same. Steam to effect the balancing is admitted to the underside of the piston 32 directly connected to the valve 31, and is controlled by the secondary valve 33 on the main valve stem 34.

30 Steam for balancing purposes should be as dry as possible and for this purpose is taken from near the top of the valve housing by means of the conduit 35 cast integral with and along the outside of the casing 28. It 35 reaches to the level of the main valve.

In order to operate the valve stem, which is guided for vertical movement, a bell crank is resorted to, one arm 37 of which is within the housing and the other arm 38 of which 40 is outside of the housing. The inner arm is bifurcated as at 39 to straddle the valve stem 34 and has each arm longitudinally slotted to engage with the cross-pins 40 on the collar 41 secured to the upper end of the valve stem.

45 The inner arm of the bell crank is connected to the outer arm by means of the torsion shaft 42 which is arranged in the offset chamber 43 in the front wall of the valve housing. This shaft has its bearings in the thimble 44 pressed in the boss 45 and in the bushing 46 passing through the wall 47 of the housing and bolted thereto by means of the flange 48. The shaft is made steam-tight 50 where it passes through the bushing by means of the plano-convex washer 49. Steam pressure on the flange 50 on the shaft presses this flange against the washer, and the washer against a seat at the inner end of the bushing 46. Power to operate the valve is applied 55 through the pull rod 51 pivoted to the lower end of the outside arm 38.

60 It is of extreme importance that provision be made in locomotive construction for expansion and contraction of the parts subject

to temperature changes. The locomotive illustrated in Figure 1 is intended for use with steam pressures as high as 450 pounds to the square inch, and it will be seen that the temperature range is thus very great. The 70 drum 14 which takes the place of the customary steam dome and supplies substantially dry saturated steam to the throttle valve housing is attached to the boiler by the large fitting 15 near the rear end of the boiler barrel and near the center of the drum. The 75 whole forward end of the drum 14 is unattached to the boiler barrel, and it is arranged to have this end as well as the throttle valve housing supported only by a sliding support 80 which rests on the boiler barrel. This support is illustrated in Figures 2 and 3 where the casting 25 forming the housing for the throttle valve has arranged thereon the integral feet 52 which extend below the bottom 85 of the casting and are adapted to rest on the boiler barrel to carry the load of the throttle valve and of the forward end of the drum. They merely rest on the boiler barrel so that 90 relative movement can take place between the parts, thus insuring that there will be no strains on the drum or the throttle valve housing other than those imposed by normal steam pressures.

95 From the above description it will be seen that the various features and objects of the invention are effectively embodied in the novel construction and arrangement.

Having thus described the invention, what is claimed as new and desired to be secured by Letters Patent is:

1. In a locomotive having a boiler, a smoke-box and a superheater within said smoke-box, the combination of a throttle valve entirely outside of said boiler and indirectly connected thereto to control the flow of steam therefrom, and a conduit connecting the exit side of said valve to said superheater and passing through the wall of said smoke-box.

105 2. In a locomotive, in combination, a boiler barrel, a steam drum outside of, substantially parallel to and in communication with said barrel, a closure for and outside of the forward end of said drum, said closure comprising a housing for the throttle valve.

110 3. In a locomotive, in combination, a boiler barrel, a steam drum above and in communication with said barrel, the forward end of said drum being free, a closure for the forward end of said drum, said closure comprising a housing for the throttle valve, and means on said closure to slidably support said drum from said barrel.

115 4. In a locomotive, in combination, a boiler barrel, a steam drum surmounting said barrel, a throttle valve at one end of said drum, a housing for said valve closing the end of said drum, said housing having two oppositely disposed steam outlets.

120 5. In a locomotive, in combination, a boiler

barrel, a smoke-box, a steam drum surmounting said barrel, a throttle valve at one end of said drum, a housing for said valve closing the end of said drum, said housing having two oppositely disposed steam outlets, and a conduit secured to each outlet and passing into said smoke-box.

6. In a locomotive, in combination, a boiler having an external steam drum, a throttle valve housing closing one end of said drum, a valve in said housing, balance means below said valve adapted to receive steam from beneath and means in said housing to supply balance steam thereto from near the top of said housing.

10 7. In a locomotive, in combination, a boiler barrel, a smoke-box at the front end thereof, a superheater in said smoke-box, a steam drum outside of said barrel but in communication therewith, a throttle valve on the end of said steam drum and close to the junction of said barrel and smoke-box, and a conduit from said valve to said superheater, passing through the wall of said smoke-box.

20 8. In a locomotive, in combination, a boiler barrel, a smoke-box at the front end thereof, a cylinder adjacent said smoke-box, a horizontal steam drum outside of and substantially parallel to said boiler barrel, a throttle valve housing closing the forward end of said drum, and a conduit from said housing to said cylinder, said conduit passing through said smoke-box.

25 9. A housing for a locomotive throttle valve, comprising a unitary casting including a sleeve adapted to be secured to a steam drum, a hollowing body portion coextensive with said sleeve, a leg to support said housing and drum from the locomotive boiler, a steam conduit extending from said hollow body portion, and integral means to cooperate with the valve proper and the said conduit.

30 10. In a locomotive, in combination, a boiler, a saturated steam drum extending longitudinally over said boiler, a throttle valve having a housing including a body portion, a sleeve extending from said body portion and attached to said drum, conduits extending laterally from said housing, and a valve member in said housing to control the flow of steam from said drum to said conduits.

In testimony whereof I hereunto affix my signature.

55 WILLIAM F. KIESEL, JR.
